UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DIVERTIBLE-HOPPER DUMP-CAR.

1,063,955.

Specification of Letters Patent. Patented June 10, 1913.

Application filed June 17, 1912. Serial No. 704,068.

To all whom it may concern:

Be it known that I, ARGYLE CAMPBELL, a citizen of the United States, residing in Chicago, in the county of Cook and State 5 of Illinois, have invented a new and useful Improvement in Divertible-Hopper Dump-Cars, of which the following is a specification.

This invention relates to improvements 10 in hopper bottom cars which may be used for either central or side dumping, and which are adapted to haul all classes of material, such as coal, ballast and other granulated forms of material, or lumber or 15 pipes.

The object of the invention is to provide a car of the type above outlined, which will be suitable for all of the purposes specified, and which will contain suitable devices for 20 diverting the material, when used for dumping, to either the sides or the center of the car.

The invention furthermore consists in the improvements in the parts and devices, 25 and in the novel combinations of parts and devices herein shown, described or claimed.

In the drawings forming a part of this specification, Figure 1 is a partial plan view of a car embodying my improvements. Fig. 30 2 is a side elevation of the structure shown in Fig. 1, a portion of the car being shown in section at the right hand end thereof. Fig. 3 is a transverse, vertical section, upon an enlarged scale, taken on the line 3—3 35 of Fig. 2, one door being open, and Fig. 4 is a longitudinal vertical section taken substantially on the line 4—4 of Fig. 1.

In the drawing, A represents the body of the car, the same being supported on suitable underframing, and as shown is provided with a plurality of hoppers B, B, the same being arranged in series longitudinally of the car on each side of the center sill and between the trucks. The car may also 45 be provided with removable broad partitions C, C, when especially heavy materials are being carried and it is not desired to use the entire length of the car, these partitions C, C, as shown, being disposed at the ends 50 of the series of hoppers B, B. Each hopper B is composed of two end hopper sheets 11, 11, the same, as shown more clearly in Fig. 3, having vertical inner edges and a downwardly sloping under edge, and each hopper 55 is furthermore provided with a perma-

nent hopper bottom sheet 12 adapted to direct the material toward the center of the car between the trucks 13, 13. Each hopper B is also furthermore provided with a side door opening D and a center door opening 60 E, the side door openings D being adapted to be closed by means of doors 14 hinged preferably at their inner lower edges at points adjacent the upper edges of the bottom hopper sheets 12, and the center door 65 openings E being adapted to be closed by hinge doors 15, 15, preferably pivoted at their upper longitudinal edges adjacent the lower outer edges of the central hopper sheets 16, 16, located on opposite sides of 70 the center sill 17.

Each series of side doors 14, 14 is adapted to be operated from a common operating shaft 18, extending longitudinally of the car at the side thereof and connected to 75 each of the doors by means of a plurality of links 19, 19, hook 20 and link 21, the latter links, as shown, extending upwardly beyond the free edges of the doors 14 while in the open position. Both series of the center 80 doors 15, 15 are adapted to be operated simultaneously from a single operating shaft 22 located beneath either series of bottom hopper sheets 12, and having keyed thereto levers 23 extending on both sides of the 85 shaft, and, having pivoted thereto at each end connecting members 24, 24 to each of the doors 15, 15, said lever and connecting members 24 being so arranged as to form a self locking arrangement on the shaft when 90 the doors are in closed position, as is customary in this type of door operating mechanism. Each of the operating shafts 18, 18, and the operating shaft 22 is adapted to be operated by any suitable form of lever 95 and ratchet mechanism.

In order to divert the granulated materials to either the center or the sides of the car, each hopper B is provided with an auxiliary or false door F, the latter being pivoted at its lower edge directly above the pivot points of the side doors 14, 14, and said false door F, as shown, is adapted to assume the position shown in full in the left hand side of Fig. 3, and to be held in this 100 position in line with the upper hopper sheets 16, as by means of a plurality of latches 25, 25, the latter being pivoted to the false doors F and adapted to be retained in place frictionally, and when extended beyond the free 105

edge of the false door F, to seat upon the upper hopper sheets 16 and thus prevent any of the material from passing out of the center door openings E, E. When, however, it is desired to dump the material to the center of the tracks, the false doors F, F are swung to the position shown in dotted lines at the left of Fig. 3, so that when the center doors 15, 15 are opened, all the material will be deflected or diverted to the center of the track by means of the hopper bottom sheets 12, 12. As will also be noted, the false doors F, F are made of such a width that when the latches or locking members 25, 25 are swung inwardly on the false doors, the latter will pass through the side door openings D, D of the hoppers with the doors 14, 14, when the latter are opened, in this way adapting the car to be used as a side dump car, and still have some of the material carried by the hoppers, which may be dumped at the center of the car by opening the doors 15, 15, if desired.

As will be seen in Fig. 4 of the drawings, the top faces of the cross members 26, 26 between the hoppers are arranged at the same level as the end floor portions 27 of the car, so that pipe, structural iron or other similar material may be easily carried by the car.

Various changes and modifications may be made in the details of the structure without departing from the spirit of the invention, and all changes and variations are contemplated as fall within the scope of the claims appended hereto.

I claim:—

1. In a car of the class described, the combination of a car body having a hopper located below the floor level of the car and provided with door openings arranged on opposite sides thereof, hinged doors for closing said openings and a hinged false door located within the hopper and adapted to close one of the openings to thereby cause the material to pass out of the other door opening, substantially as specified.

2. In a car of the class described, the combination of a car body having door openings and doors for center dumping and door openings and doors for side dumping and arranged to form a longitudinal series of hoppers along each side of the longitudinal center of the car, and auxiliary doors pivot-

ally mounted and movable from one position to another into line with the bottoms of the hoppers, substantially as specified.

3. In a car of the class described, the combination of a car body provided with door openings and having doors for side and center dumping, movable false doors used to cover portions of the hoppers when the car is arranged for side dumping, whereby a continuous incline is formed from points adjacent the top of the longitudinal center of the car to the outer edges of the side dumping doors when the latter are opened, substantially as specified.

4. In a car of the class described, the combination of a car body having longitudinally arranged hoppers on each side of the longitudinal center line of the car, each hopper having a side dumping door hinged at its bottom to a hopper bottom sheet inclined downwardly toward the center of the car and a center dumping door hinged at its top, said center door abutting the said hopper bottom sheet at its lower edge, substantially as specified.

5. In a car of the class described, the combination of a car body having hoppers provided with door openings and doors for side dumping and door openings and doors for central dumping, inclined hopper sheets between the side and center doors in each hopper, and movable members for directing the flow of material through either the side or center openings of the hopper and adapted to form continuous inclines with the center longitudinal hopper sheets, substantially as specified.

6. In a car of the class described, the combination of a car body having longitudinal hoppers along the sides of the center sills arranged for central and side dumping, auxiliary hinged doors for preventing the flow of material through the center doors of the hoppers when said auxiliary doors are in position to form a continuous incline with the center hopper sheets of the car toward the outside of the track, and for permitting the flow of material through said center doors when said auxiliary door is otherwise positioned, substantially as specified.

ARGYLE CAMPBELL.
